(57) **CLAIM**

The ornamental design for a multiple tier over the sink dish rack, as shown and described.

DESCRIPTION

FIG. 1 shows an elevational perspective view of a multiple tier over the sink dish rack.

FIG. 2 is a front view of the two tier over the sink dish rack.

FIG. 3 is a rear view of the two tier over the sink dish rack.

FIG. 4 is a left side view of the two tier over the sink dish rack.

FIG. 5 is a right side view of the two tier over the sink dish rack.

FIG. 6 is a top view of the three two tier over the sink dish rack; and,

FIG. 7 is a bottom view of the two tier over the sink dish rack.

The broken lines shown in the drawings represent portions of the multiple tier over the sink dish rack that form no part of the claimed design.
